UNITED STATES PATENT OFFICE

JEREMIAH LEE BAUSHER, OF READING, PENNSYLVANIA, ASSIGNOR TO INFANT SOCKS, INC., OF READING, PENNSYLVANIA, A CORPORATION OF DELAWARE

STOCKING

Application filed May 12, 1930. Serial No. 451,617.

My invention relates primarily to infants' socks or the like, and more particularly to an improved article of this nature, and the method of knitting the same to produce a sock having a neat fixedly folded-over rib-knitted cuff portion that will maintain its shape under all conditions and provide an increased elasticity over the elasticity of the leg portion sufficient to support the latter on the leg of the wearer.

Stockings have heretofore been formed with a so-called "turned welt" produced by folding over during the process of knitting a top portion of the leg and re-engaging its end loops on the needles to interknit them with the next leg course produced.

And half hose have heretofore been formed with a top portion of ribbed fabric having the loops at one end integrally united to the leg portion by a preliminary transfer of said loops to the knitting needles of the leg forming machine.

Neither of the above known tops however form a satisfactory turned-cuff top desirable alike for its increased elasticity to support the short sock or hose on the leg of the wearer, and as a neat ornamental finish for said sock top. The turned-welt is obviously of the same knit fabric as the leg portion and lacks the necessary increased elasticity desired for supporting the sock, and moreover has not sufficient body essential for proper effect of the ornamental cuff. The ordinary ribbed top, when folded over, not only undesirably exposes the differently appearing reverse side of the fabric, but such folds require care to insure a neat appearance, and when not fixedly held are subject to ready displacement causing an unsightly and neglected effect.

My improved sock with its fixedly held turned cuff top not only provides the desired ornamental effect and increased elasticity, but constantly maintains such neatly turned effect even when hastily drawn on the leg by the inexpert hands of a very young child. And the reverse side of my turned cuff may have the identical finish as the normally exposed side, which will permit of an additional turn down if desired without change in appearance.

With the above advantages outlined, and with others that will appear as the description progresses, my invention comprises the improved turned cuff sock or hose and the method of knitting the same as hereinafter more fully described in connection with the accompanying drawing, the novel features thereof being fully set forth in the appended claims.

Referring to the drawing:

Fig. 1 is a side elevation of a child's sock or short hose embodying my improvements, a portion of one side thereof being broken away to clearly show the inside face of the underlying side.

Fig. 2 is an enlarged diagrammatic perspective view of a fragmentary portion of the top of the sock shown in Fig. 1, indicating the integral junction of the cuff and leg portions.

Fig. 3 indicates a suitable cut-off length of a separately knitted ribbed fabric strip, adapted when folded over to form my improved cuff portion of the sock.

Fig. 4 indicates a convenient means for transferring the end loops of my improved cuff portion to the needles of a leg knitting machine, by use of a known quill ring or transfer bar.

Referring more particularly to Figs. 1 and 2, my improved sock or short hose comprises a usual foot portion 5 and leg portion 6, with a ribbed-fabric turned-cuff portion 7 having the loops at both its ends 8 and 9 interknit with the top course of loops of the leg portion 6 to integrally unite said cuff to the leg and fixedly determine and maintain the neatly folded cuff portion 7.

And in forming this cuff portion 7, the upper half of the length of ribbed fabric employed, is preferably folded inwardly and downwardly so that the normally exposed and reverse faces of said cuff will have the same identical surface finish.

In forming the junction of the ends 8 and 9 with the top course of loops of the foot portion 6, if all the loops of said ends are transferred to the needles, it may in some cases produce too heavy a suture course for a slightly appearance besides putting too

heavy a strain on the thread of the leg portion. I therefore preferably engage only some or half of the loops of the inner end 9 with the needles, leaving the intermediate 5 loops unengaged. Such partially engaged series of loops is sufficient to securely unite the edge 9 so that it cannot become free, and the nature of this ribbed fabric is such that ravelling of the unengaged loops is impossible, the direction of ravelling being from the reverse end 8 ordinarily. Some commercial rib-knitted strips are formed with several courses, adjacent the lines of severance into individual top lengths, in which the 15 loops are alternately arranged and of half the number of adjacent courses. Employing such special courses as transfer loops for the end 9, all may be engaged if desired, arranged on alternate needles of the machine.

20 A sock thus embodying my improvements always has a neatly appearing turned cuff portion not subject to unsightly displacement or improper folding; forms a strong integral structure; and provides desired adequate elasticity in the top portion to support the sock on the leg in proper stretched condition. While shown and described as a child's sock, it is obviously equally applicable to any hose employing a top cuff portion of 30 elastic ribbed fabric.

To conveniently and economically produce my improved sock above fully described, I employ the following preferred method: Fig. 3 indicates a suitable cut-off length of ribbed fabric preferably having a full course of loops 10 at one end thereof and a course of half the number of loops 11 at the other end, alternately spaced with relation to said full course loops. Such half course series of loops 40 have heretofore been employed in a usual ribbed fabric to guide proper cutting-off of top lengths and to facilitate ravelling in a normally reverse direction back to a selvage or non-raveling course heretofore employed 45 as the finished top edge of the ribbed stocking top. By folding over inwardly and downwardly the upper half of said length of ribbed fabric on the transverse line 12—12 I produce the turned cuff for my sock. And to facilitate 50 the transfer of the loops 10 and 11 to the needles of the leg knitting machine, I employ a usual quill ring or transfer bar in known manner. Fig. 4 indicates such a quill ring 55 having the loops 10 engaging all the points 16 of the latter, and the loops 11 engaging alternate ones of said points, said loops being readily pressed off from said points to the needles 17 of a leg knitting machine for subsequent knitting of the leg and foot portion 60 as heretofore. When the ribbed fabric is not formed with the special loops 11, I simply engage selected ones of the full course on the points 16, leaving the intermediate ones unengaged, as ravelling is normally effected 65 from the reverse end having loops 10. The

loops 11 are preferably on the inner end 9 of the turned cuff, and are sufficient to firmly secure said end to the leg portion 6 while reducing the number of double loops necessarily engaged by the loops of said top leg 70 course.

From the foregoing description it is believed the nature of my improved sock and the method of its production will be readily understood. The advantages of my improvements have heretofore been stated, and the novel features thereof are fully set forth in the following claims.

What I claim is:

1. As a new article of manufacture, a knitted stocking comprising separately knitted top and leg portions, said top portion being formed by an intermediately folded strip of rib-knitted fabric, said rib-knitted strip having a full course series of loops at one end and 80 a series of a reduced number of spaced loops at the other end, and both said series of loops being interknitted with the first course of the plain-knitted leg portion of the stocking, said full course series engaging with every 90 loop of said first course and said reduced number series with spaced loops of said first course.

2. The process of knitting a stocking having a separately knitted intermediately folded welt of rib-knitted fabric and an integrally united plain-knitted leg and foot portion, which consists in intermediately folding a cut-off strip of rib-knitted fabric, transferring the loops at both ends of said strip to 100 the needles of a plain knitting machine, and thereafter knitting a plain-knit leg and foot portion on said needles.

3. The process of knitting a stocking having a separately knitted intermediately folded welt of rib-knitted fabric and an integrally united plain-knitted leg and foot portion, which consists in intermediately folding a cut-off strip of rib-knitted fabric having at one end thereof a full course series of 105 knitted loops and at the other end a spaced series of knitted loops of reduced number, transferring both said series of loops to a series of needles of a plain knitting machine, said full course series of loops engaging with every needle and said reduced number series 110 engaging spaced needles of said series, and thereafter knitting a plain-knit leg and foot portion on said needles.

In testimony whereof I affix my signature. 115
JEREMIAH LEE BAUSHER.
